PULL

La Verne E. Clayton, Rockford, Ill., assignor to Amerock Corporation, Rockford, Ill., a corporation of Illinois

Filed Aug. 29, 1960, Ser. No. 61,919

Term of patent 14 years

(Cl. D10—8)

FIG. 2 is a top plan view of the pull.

FIG. 3 is an enlarged side view.

FIG. 4 is a perspective view.

FIG. 5 is an enlarged sectional view taken along the line 5—5 in FIG. 1.

FIG. 6 is an enlarged sectional view taken along the line 6—6 in FIG. 2.

I claim:

The ornamental design for a pull, substantially as shown.
